R. S. HILAIRE

GAS COCK

Filed May 13. 1922

Rodolphe S. Hélaire Inventor

By William C. Sinton

Attorney

UNITED STATES PATENT OFFICE.

RODOLPHE S. HILIAIRE, OF MONTREAL, QUEBEC, CANADA.

GAS COCK.

Application filed May 13, 1922. Serial No. 560,810.

To all whom it may concern:

Be it known that I, RODOLPHE S. HILIAIRE, a subject of the King of Great Britain, residing at Montreal, Province of Quebec, Canada, have invented certain new and useful Improvements in Gas Cocks, and I do hereby declare that the following is a full, clear, and exact description of the invention, such as will enable others skilled in the art to which it appertains to make and use the same.

This invention relates to improvements in gas cocks and especially to a safety gas cock of the type which is locked in its closed position in such a manner that it cannot be accidentally moved therefrom.

The principal object of the invention is to provide a gas cock of the character indicated which will be simple and practical in its structural nature, and readily operated to open position when desired.

A further object of the invention is to provide an arrangement in a gas cock which will prevent the loosening of the valve plug and the consequent escape of gas upon continued turning of the plug.

The invention is fully disclosed in the following specification, of which the accompanying drawings form a part, and in which:

Figure 1 is a side elevation of the device; Figure 2 is a central vertical section therethrough;

Figure 3 is a detail of Figure 2 showing the parts in closed position;

Figure 4 is a view similar to Figure 3 showing the parts in open position;

Figure 5 is a plan taken on Figure 1;

Figure 6 is a perspective view of the handle showing the inner end thereof;

Figure 7 is a section on the line 7—7 of Figure 2;

Figure 8 is a section on the line 8—8 of Figure 3;

Figure 9 is a perspective view of the locking pin;

Figure 10 is a similar view corresponding to Figure 4;

Figure 11 is a fragmentary elevation, partly broken, showing the safety spring; and, Figure 12 is a perspective view of the valve plug, showing the gas passage in particular.

Referring to the accompanying drawings by reference characters throughout, the numeral 1 indicates the usual body having

a recess 2 therein on which is seated a valve plug 3, the latter being adapted for rotation in the usual manner. A locking pin 4 extends longitudinally through the central portion of the plug and is adapted for reciprocation therein. The lower end of the pin is provided with a key 5 which normally seats in a notch 6 formed in the bottom of the body. The upper end of the plug receives a handle 7 rotatably connected thereto by means of the screw 8. A pin 9 which extends laterally from the upper end of the locking pin projects into a curved groove 10 formed in the inner end of the handle. It will be seen from Figure 10 that the lower surface 11 of this groove is in the nature of a cam and that rotation of the handle 7 will therefore result in the lifting of the key 5 out of the notch 6, whereby the valve plug is unlocked. A circular groove 12 is formed in the upper end of the plug and contains a spring 13, one end of which is fastened to the plug, while the other end extends into an aperture 14 formed in the inner end of the handle. This spring is adjusted so that it tends to close the valve when the key 5 is over the notch 6, as shown in Figure 2. It will be noted that a groove 15 is cut in the plug for the accommodation of the upper end of the locking pin, as the latter reciprocates. When the key is released in the manner described, the valve plug may be turned by means of the handle, whereby communication is established between the ports 16 and 17 through the curved passage 18 formed in the surface of the valve plug and extending a sufficient distance around the same to allow a free passage of gas between the ports.

The intermediate portion of the plug is reduced as at 19, forming a shoulder 19. A spring 20 surrounds this shoulder, while a nut 21 is threaded upon the upper end of the body, thus drawing the latter into close engagement with the plug for preventing the escape of gas. In order that the nut 21 may not work loose as the valve plug is turned, a slot 22 is cut in the threaded end of the body and the end of the spring is bent and forced therein as at 23. This arrangement prevents the spring from turning, although the pressure thereof is not thereby affected. The body is also slotted beneath the threaded end, as at 24, for the

reception of a pin 25 formed on the valve plug, for limiting the turning movement of the latter.

While a specific embodiment of the invention has been illustrated and described, it is to be understood that various alterations in the details of construction may be made without departing from the spirit of the invention as indicated by the appended 10 claims.

Having thus fully described the invention, what I claim as new and desire to protect by Letters Patent is:—

1. A gas cock comprising a body having 15 a notch formed in the bottom thereof, a valve plug rotatably mounted in said body, a handle rotatably mounted in the plug, a locking pin adapted for reciprocation within the plug and having its lower end normally seated in the notch, and means for lifting said pin from the notch upon the rotation of the handle.

2. A gas cock comprising a body having

a notch formed in the bottom thereof, a valve plug rotatably mounted in said body, 25 a handle rotatably mounted in the plug and having an inclined groove in its inner end, a key adapted for reciprocation within the plug and having its lower end normally seated in the notch, and a pin projecting 30 laterally from the upper end of the key into the groove.

3. A gas cock comprising a body having a notch formed in the bottom thereof, a valve plug rotatably mounted in said body, 35 a handle rotatably mounted in the plug, a locking pin adapted for reciprocation within the plug and having its lower end normally seated in the notch, means for lifting 40 said pin from the notch upon the rotation of the handle, and a spring engaging the handle and plug for normally holding the latter in closed position.

In witness whereof I have hereunto set my hand.

RODOLPHE S. HILAIRE.
